Renewed October 16, 1934

16 Claims. (Cl. 155—79)

This invention relates to improvements in chairs and more particularly to improvements in chairs of the type adapted to be suspended from a main supporting structure.

5 An object of the invention is to provide a chair which is capable of being collapsed into a very small package.

Another object of the invention is to provide a chair which can be adapted to a supporting 10 structure and which can be collapsed into a small package and locked in such collapsed position by means of an attaching member.

Another object of the invention is to provide a chair, the parts of which can be collapsed, 15 with such configuration of essential parts that correct posture of the occupant is assured.

Another object of the invention is to provide as an auxiliary part of a chair a combined foot rest and leg exerciser for the occupant thereof.

20 The present invention in any of its forms, comprises a chair which of itself does not possess any legs or other independent supporting parts but which is provided with an attaching member whereby the chair can be attached to an independent supporting member.

25 The chair is composed principally of a frame to be positioned, when the chair is in use, in a substantially horizontal plane; to which frame are secured side members and a seat as well as an attaching member. The side parts are so connected to the seat and to the frame that the sides and seat can be collapsed into a position substantially within the confines of the frame. In one form 30 of the invention, it is not necessary to provide a separate back for a chair since when the parts thereof are expanded the seat moves rearwardly in an amount sufficient to contact with the main supporting member, so that it is held against further backward movement and against rocking.

35 In another form of the invention a separate back is supplied and in addition thereto a spacer may be utilized for holding the seat in proper position relative to the supporting structure.

40 In all forms of the invention, the seat of the chair is so shaped as to cause the legs of the occupant to extend downwardly in normal correct posture. To the underside of the seat may be secured a combined foot rest and leg exerciser in the nature of a cross bar arranged for vertical movement and resiliently pressed upwardly. The cross bar will yield to the pressure of the feet of the occupant but will normally tend to force the feet and legs upwardly. The attaching member is of a type adapted to fit over a supporting structure such as a large chair and may

be adjusted to accommodate itself to various sizes and configurations of supporting structure. This attaching member is hinged to the frame of a chair approximately in mid center of the rear portion of the frame thereof and is capable not only of pivotal movement but also of a sliding movement as a result of which it is possible to hold the parts of a chair in their collapsed position by the confining action produced by the attaching member.

45 Other features, objects, and advantages of the invention will become apparent by reference to the following detailed description taken in connection with the accompanying drawings forming a part of the same wherein,

50 Fig. 1 is a perspective view of an embodiment of the invention showing the same attached to a support such as a chair.

55 Fig. 2 is a plan view of a device embodying the invention.

60 Fig. 3 is a section taken substantially on the line 3—3 of Fig. 2.

65 Fig. 4 is a section taken substantially on the line 4—4 of Fig. 3.

70 Fig. 5 is a vertical section of the device in collapsed position.

75 Fig. 6 is a section taken substantially on the line 6—6 of Fig. 5 and including a complete vertical section of the device in collapsed position.

80 Fig. 7 is an enlarged perspective view showing one form of securing attaching members to the device.

85 Fig. 8 is an enlarged perspective view showing another method of securing an attaching member to the device.

90 Fig. 9 is a vertical section of the arrangement shown in Fig. 8, the respective positions of the attaching devices being indicated.

95 Fig. 10 is a front elevation of a modified form of the invention.

100 Fig. 11 is a section taken substantially on the line 11—11 of Fig. 10.

105 Fig. 12 is a perspective view of a further modification of the invention.

110 Fig. 13 is a section taken substantially on the line 13—13 of Fig. 12, and

115 Fig. 14 is a section taken substantially on the line 14—14 of Fig. 12.

120 Referring now to the drawings and particularly to Figs. 1 to 6, inclusive, 10 indicates generally a chair incorporating the present invention, which chair is composed of a frame (preferably wooden) made up of four bars 11, 12, 13 and 14, joined together in any suitable manner to form substantially a rectangle. This frame acts as a support 125

for an apron 15 and also for a seat 16, which is secured to the frame in a manner to be described in detail hereinafter. The apron 15 may be pivotally mounted within the frame about an axis 5 defined by the screws 17, so that it can be lifted out of the way of the occupant of the seat. A pair of stop members 18 fastened in the frame members 12 and 14 limit the pivotal movement of the apron and provide rests to hold the same 10 substantially in horizontal position.

The seat 16 is made up preferably of wood having its side edges rounded as indicated at 20. The seat 16 is secured to the frame of the chair by means of a pair of similar hangers 21, preferably made of metal and shaped as shown in the drawings, that is, with a double bend 22 at one end and a single bend 23 at the other end. The curvature of the bend 23 corresponds closely to the curvature 20 of the seat edges so that a 15 pivotal movement of the hangers 20 about the seat can be carried out. The double bend 22 is of such shape as to permit engagement thereof about the side bars 12 and 14 of the frame. The hangers are secured to the seat 16 by means of 20 spaced pairs of screws 24 which pass through slots 25 in the ends of the hangers having the bends 23. These slots 25 are of such length as to permit the hangers to remain in the position shown in full lines in Fig. 4, or in the position shown in 25 broken lines in the same figure.

Extending through the side bars 12 and 14 are spaced pairs of guide members 26 which are in the nature of bolts having heads 27 spaced from the inner surfaces of the side bars. The hangers 30 21 are provided with slots 28 which are of slightly greater width than the diameter of the bolts 26. The slots 28 have substantially vertical portions near the ends thereof with inclined portions between the vertical portions as shown clearly in 35 Fig. 3. The purpose of these inclined cam slots 40 will be explained hereinafter.

Secured to each hanger 21 is a side member 30, preferably made of wood, which members serve the purpose of preventing contact between 45 the body of one seated in the chair and the metal hangers 21. These side pieces 30 are provided with recesses 31 which are cut in the surfaces resting against the hangers 21 and which correspond in configuration to the slots 28. The recesses 31, however, are wider than the slots 28 and are of such depth as to receive the heads 27 of the bolts 26.

Secured to the frame member 13 are a pair of angle bars 35 made of metal, and having extending upwardly therefrom studs 36 shown clearly in Fig. 7. The studs 36 are spaced a slight distance from the top of the angle of the bars so that slotted members 37 can be engaged with the connecting part of the stud. The members 37 are substantially Z-shaped, and are provided with slots 38 which extend a part of the length of the intermediate portion of the members and into one toe portion thereof. The other toe portion of each member is provided with a slot 39 which permits the passage therethrough of bolts. As shown in Fig. 1, the members 37 have secured thereto a complementary member 40 which is slotted as shown, the members 37 and 40 being secured together by bolts and wing nuts 41. The slots 39 in the members and the slots in the member 40 permit adjustment of the composite attaching member to adapt it to different conditions.

The exerciser of the present invention consists 75 of three rods 45 which are pivotally secured to the

underside of the seat 16 by means of a shaft 46 journaled in brackets 47 fastened to the seat. Slidably on the rods 45 is a bar 48 which is pressed upwardly by springs 49 positioned between the bar and knobs 50 on the end of rods 45. While in the drawings the exerciser has been illustrated as being provided with two springs 49 positioned around the outside rods 45, it will be evident that a single spring might be used, such spring being positioned around the central rod 45, or in some cases each rod might be provided with a spring. An apron 15 may be provided with a central aperture 51 into which may be placed a dish 52. The seat 16 may be provided with an aperture 52 in which can be located a commode 15 53. Clips 54 secured to the underside of the seat 16 aid in retaining the commode into position. A cover 55 formed of the same material as the seat, is hingedly secured thereto as indicated at 20 56 for closing the aperture 52 when the commode 20 is not in use.

A strap 57 has one end fastened to the seat 16 and the other end removably fastened to the underside of the apron 15 for aiding in retaining an infant in the chair.

By inspection of the drawings, it will be observed that the inner edge of the apron 15 is shaped so that the mid portion thereof is curved inwardly as at 58, while the outer edge of the seat 16 is shaped in corresponding fashion, that 30 is, with an outwardly curved part 59 and receding curved parts 60. Since both the apron and the seat are made of wood, it will be evident that the two parts of the chair may be cut from a single piece of material since the curvature of the 35 apron corresponds exactly to the curvature of the seat. By having these curvatures correspond, the seat and apron can be cut from a piece of material by one cutting operation with the resultant decrease in waste of material.

The device is so arranged as to be capable of being collapsed into the position shown in Figures 5 and 6, or to be expanded into the position shown in Figures 1 to 3. When the device is expanded, the seat may be held against rocking 45 motion by means of sliding lock 65, which engages in a recess 66 cut in one of the double bends 22 of a hanger 21.

The device when expanded assumes the position shown in the drawings and when in this 50 position it may be attached to any suitable supporting member such as a chair 70. The method of attachment is very simple, since it is only necessary to engage the composite attaching member over the back of the chair as shown in 55 Figure 1. Adjustment may be made of the composite attaching member to insure that the frame does not rock but is held in a substantially horizontal position. When the chair is attached to a supporting member such as a larger chair, it will 60 be apparent that the seat 16 depends from the frame, being supported by the hangers 21 which have parts folded over the side bars 12 and 14. In this position the rear edge 72 of the seat 16 is substantially in line with the rear surface of 65 the bar 13. Since the limits of the bar 13 and the side 72 are in substantially vertical alignment, it will be apparent that the seat will press against the back of the chair 70 so it is not necessary to provide a separate back for the small chair. As 70 before stated, tilting of the seat 16 is substantially prevented by the movement of the lock 65.

When it is desired to collapse the chair, the seat 16 is pushed upwardly toward the frame of the device, which upward motion results in 75

a sliding movement of the hangers 21 upwardly disengaging their parts 22 from the side bars 12 and 14. As these hangers 21 are forced upwardly their movement is slightly forward due to the 5 inclination of the cam slots 28. During this movement of the hangers, the seat 16 approaches the frame with a rectilinear movement. Since the cam slots 28 extend downwardly into the bend 23 of the hangers, it is possible to move the seat 16 upwardly into the actual confines of the frame. When the seat has been moved upwardly 10 into the position shown in Figures 5 and 6, the hangers can be rotated inwardly through an angle of approximately 90 degrees. This is made possible by the extended cam slots 28 and by the slots 25 which engage the guide members 24 on the seat. When the hangers have been folded through approximately 90 degrees, they assume the positions shown in Figures 5 and 6, in which 15 it will be seen that the side pieces 30 lie flat against the top of the seat 16. The exerciser may then be folded rearwardly until the bar 48 and the ends of the rods 45 lie against or adjacent the underside of the seat 16. When the parts 20 have assumed this position, they may be locked therein by movement of the composite attaching part from the position shown in Figure 3 to that shown in Figure 5, the slots 38 in the member 37 permitting such movement. If desired, the 25 attaching part can be clamped to hold the parts in placed position quite clearly by a simple adjustment through the agency of the bolts and wing nuts 41.

In this position the chair occupies a very small 30 space, that is, a space only a slight bit greater than the over-all dimensions of the frame. For this reason the device is capable for ready transportation, and since it can be set up with a minimum number of motions, it adapts itself to a 35 great number of uses.

When it is desired to attach the chair to a supporting structure the following steps may be carried out. The composite attaching member is moved out of locking engagement with the exerciser and other parts and is turned into the 40 position shown in Figure 3. The exerciser is then free to swing downwardly. The seat may next be lowered into the position shown in Figures 1 and 3 by simply rotating the hangers 21 through approximately 90 degrees from the position 45 shown in Figure 6. The seat is pushed downwardly until the bends 22 of the hangers engage over the bars 12 and 14. If desired, the apron 50 15 can be rotated upwardly so that an occupant can be seated in the chair more easily. Once the occupant is seated, the apron can be held against upward movement by attaching one end of the strap 57 to the underside thereof.

In some instances it may be desired to make 55 use of a different attaching part for attaching the chairs to objects of different configurations. To facilitate the removal of the composite attaching member, the slots 38 in the members 37 may be provided with a T-head as at 39' (Figure 7) which will permit disengagement of both 60 members 37 from the studs 36 without disconnecting the part 40 from the parts 37. When the composite attaching members have been removed, one of any desired shape can be secured 65 to a chair in a similar manner to adapt the chair for use in connection with the back of an automobile seat or other desirable locations.

A simple form of attaching member is shown 70 in Figures 8 and 9 wherein angle bars 35 secured to the bar 13 of the frame are provided with

upstanding portions 80 and curved over parts 81. The upstanding portions 80 are provided with slots 82 through which pass parts of a heavy wire 84 shaped as shown to provide an attaching member. The ends of the wire 84 are bent to fit under the curved part 81 of the angle bars when the device is used to attach the chair to a supporting member. When the chair is collapsed, the ends of the wire 84 are pressed downwardly to the lower extremity of slots 82 after which the entire 10 attaching member can be turned through an angle of approximately 90 degrees and then moved inwardly to retain parts of the chair in collapsed position. In Figure 9 the broken lines 15 indicate the position of the wire when the device is ready for attachment to a supporting member while the solid lines indicate the position of the attaching member just prior to its inward motion to locking position.

In Figures 10 and 11, a slightly modified form 20 of the invention is shown. The parts thereof which correspond to parts in the previously described embodiment of the invention are given similar reference characters with an addition of a prime to each thereof. The slots 28' are substantially vertical throughout their entire length 25 as distinguished from the inclined slots 28 before described. As a result of this change in cam slot design, the seat 16' will move toward and away from the frame of the chair without any forward or backward movement. This device has as an additional element a back member which is made up of a metal hanger 90 somewhat similar to the hangers 21, being secured to the rear edge of the seat 16' by means of guide screws 91 30 fitting in slots in the hanger. The slots in the hanger 90 correspond closely to the slots 25 shown in Figure 4. Thus it will be seen that the hanger 90 has a portion 92 which when the device is expanded fits under the seat 16' to aid in supporting the same. As integral parts of the hanger 90, a pair of ears 93 are pressed therefrom to extend rearwardly from the hanger as shown in Figure 11 and to lie substantially in the same 35 plane as the part 92. These ears 93 are adjacent each end of the hanger and are connected by a bar 94 which may engage an upright member and hold the seat 16' away from such upright member. The top part of the hanger 90 is provided with a double bend 95 for engagement over the bar 13' of the chair frame. A back member 40 45 50 55 96 similar to the side members 30' is secured to the metal hanger 90.

When it is desired to collapse the chair in this 60 form, the seat is raised upwardly until the double bend 95 and the double bends 22' are disengaged from their respective frame bars. The hanger 90 and back member 96 are then folded through an angle approximately 90 degrees to assume the 65 position shown in broken lines in Figure 11. Next the hangers 21' are folded through angles of approximately 90 degrees to cause the side pieces 30' to rest upon parts of the hanger 90. Due to the positioning of this hanger 90, the side pieces 30' under ordinary circumstances will not 70 lie flat on top of the seat 16' as in the previous embodiment but will be spaced a distance therefrom approximately equal to the combined thickness of the hanger 90 and the back piece 96. This is made possible by providing each hanger 21' with a relatively long portion extending under the seat 16' in expanded position with correspondingly longer slots through which pass the 75 guide members 24'. A pair of spaced recesses are provided in the frame bar 13' for the reception of

the heads 91 of the attaching members for the rear hanger 90, such recesses being indicated by dotted lines 97 in Figures 10 and 11.

The remaining parts of the device including the 5 apron, the strap connecting the apron to the seat, and the exerciser, are similar to those parts described in connection with the other embodiments of the invention.

The operation and use of this form of chair are 10 similar to the operation and use hereinbefore described, the only differences being that the relative movement between the frame and the seat is strictly rectilinear without the inclusion of any backward or forward motion, and in addition the 15 back member has been provided to supply a positive support for the back of the occupant. In this form of chair reliance is not placed upon contacting between the rear edge of the seat and a supporting member such as a larger chair, since 20 the connecting bar 94 between the ears 93 serves to hold the seat away from a supporting upright which is indicated in broken lines in Fig. 11.

A further modification of the invention is shown 25 in Figures 12 to 14, inclusive. This form consists of a substantially U-shaped frame 100 made preferably of metal tubing of sufficient strength to withstand the stresses applied thereto. Depending from the arms of the frame 100 are two metallic hangers 101 which are secured to the arms 30 by means of integral portions 102 rolled therearound. These portions 102 may have sliding fits with the arms of the frame. Intermediate the horizontal edges of the hangers 101 are spaced vertical slots 103. A seat 104 similar in shape to 35 seats 16 and 16' is provided. The width of the seat 104 is approximately equal to or slightly less than the distance between the inner surface of the rolled parts 102 of the hangers so that the seat can be moved into position to lie between the 40 arms of the frame.

The seat is attached to the hangers 101 by 45 means of a plurality of metallic members 105 secured in the underside of the seat and then bent to expand horizontally from the edges thereof. The horizontal parts of the members 105 are 50 spaced from the underside of the seat at a distance at least as great as the width of the hangers 101. These members 105 extend through the slots 103 and are provided with loops 106 in the ends thereof to prevent disengagement of the hangers from the seat.

This form of chair is also provided with a back 55 107 in the nature of a sheet of metal, which back is pivotally secured to the top side of the seat by means of an integral part 108 rolled around a bracket 109, the ends of which are embedded in the seat. The top part of the back 107 tapers off to a rolled part 110 shaped to fit over the frame 100 as shown in the drawings. Extending outwardly 60 from the lower edge of the back 107 and spaced from each end of rolled part 108, are integral spacers 111 which serve to hold the seat in spaced relation to a vertical support when the chair is expanded and attached to such vertical support.

Rigidly secured to the back part of the frame 65 100 are brackets 115 which have vertical portions 116 and rolled tops 117. These brackets are provided with slots in their portions 116 and in part of their rolled tops 117. Through these slots extend the ends of a wire attaching member 118, the 70 ends being bent under as indicated at 119 to prevent disengagement of the attaching member 118 from the brackets. This attaching member, due to these slots, can be rotated and then can be

pressed inwardly to hold the parts of the chair in collapsed position.

An apron 120 preferably of wood is secured to the arms of the frame 100 by means of a sleeve 121 on one edge thereof which encircles an arm of the frame and a partial sleeve 122 at the other edge thereof, which can rest on the other arm. By this arrangement of total and partial sleeves, it is possible to swing the apron upwardly about one of the arms as a fulcrum, or to slide the apron 10 toward or away from the back of the chair.

The expanded position of a chair is shown in Figure 12 in which the seat 104 is supported by the hangers 101 due to the engagement of the member 105 in the slots 103. The back 107 15 has its rolled portion 110 in engagement with the back part of the frame 100. In this position the chair may be suspended from any upright object by merely placing the attaching member 118 over this object. The spacers 111 are 20 provided to rest against the upright object or a separate upright object, and due to the sliding arrangement of the hangers 101 relative to the arms, it is possible to move the seat forwardly or backwardly a slight amount to permit adjustment thereof.

When it is desired to collapse the chair the seat is raised upwardly, which upward movement automatically disengages the rolled part 110 of the back from the frame after which the back 30 may be folded to lie flat against the top of the seat. As the seat is pushed upwardly, the hangers are drawn inwardly progressively as shown by broken lines of Figure 14 until the seat lies entirely within the confines of the frame. The 35 hangers 101 can be folded under the seat with parts thereof in the space between the bottom of the seat and the members 105. The attaching member 118 may be swung around into position to hold the parts in this collapsed relation.

If desired, a strap 122' can be used as in the previous embodiment of the invention, and also an exerciser similar to that already described can be attached to the underside of the seat 104.

While the chair of Figures 12 and 14 has been 45 described specifically as one being suitable for infants and small children, it will be apparent that the use thereof is not so limited. The chair may be constructed on a larger scale, for example, of sufficient size to accommodate an adult and 50 can be made use of at athletic events or on any other occasion wherein it is desirable to make use of temporary seating arrangements. Since the chairs can be collapsed into a relatively compact article, they can be transported very easily 55 and can be set up in a minimum space of time. The only other equipment necessary for assembling a number of these chairs consists of vertical supports of the proper character from which the chairs could be suspended.

In all of the forms of the invention described hereinbefore, a number of advantages are inherent. It is well known that babies or small children when placed in a chair like to have something upon which they can rest their feet with their legs substantially in horizontal position. It has been discovered that such practice is detrimental to the proper development to the children, and accordingly, this invention overcomes the objections just stated. By having the seat so shaped that the intermediate part of the front edge thereof is curved outwardly from receding curved parts, it becomes natural for the occupant to permit his legs to extend downwardly as shown in Figure 3. Furthermore, there 70 75 80 85 90 95 98 99

is nothing in this construction upon which the occupant could rest his feet with his legs in a substantially horizontal position. Furthermore, the chair is so shaped as to assure correct posture of the occupant. In the form shown in Figures 1 to 6, inclusive, the seat when the device is expanded, moves rearwardly a slight amount to engage the upright supporting member, and the back of the occupant is actually supported by the rear bar 13. A separate back for the chair is not necessary in this form of the device. In the arrangement shown in Figures 10 and 11 the separate back is provided, which in some instances may be desirable. The same is true of the embodiment shown in Figures 12 and 14.

From an inspection of the drawings, it will be seen that relative movement between the seat and frame is limited by the engagement of the top of the hangers over the arms in expanded position of the chair, and by contact of the seat with the guide studs in collapsed position of the chair, (Figs. 1 to 11). In the form shown in Figs. 12 to 14, the studs 106 serve to limit such movement.

In all forms of the invention, the exerciser may be attached to the underside of the chair and when so attached it becomes natural for the occupant of the chair to rest his feet upon the bar 48. The natural tendency would be to press down upon this bar, but due to the springs 49 such pressure is yieldingly resistant. Children, however, will continually press down upon the exerciser with the result that the repeated up and down movement of the legs and the feet will exercise such members very beneficially. Moreover, since the foot will engage the bar 48 approximately at the instep thereof the repeated application of pressure will very materially aid in exercising the instep of the occupant.

In the event it should be desired to convert the chair into a swing, chains or cords can be attached to eye screws 130 (Figure 2) for suspending the chair in any desired position.

I claim:

1. A chair of the type described comprising a frame, hangers provided with cam slots, guide members passing through said slots and connected to said frame to secure said hangers to said frame for slidable pivotal movement relative to the frame, a seat of smaller external dimensions than the corresponding internal dimensions of the frame hingedly secured at each side to a hanger, the hangers and the seat being movable into position substantially within the confines of the frame.

2. A chair of the type described comprising a frame providing arms, guide studs extending inwardly from said arms, hangers having cam slots engaged by said studs to slidably and pivotally connect said hangers to the arms, the ends of said hangers being bent to hook over said arms in the expanded position of the chair, and a seat of smaller external dimensions than the corresponding internal dimensions of the frame hingedly connected at each side to a hanger, said seat and hangers being movable substantially within the confines of the frame when the chair is collapsed.

3. A chair of the type described comprising a frame providing arms, guide studs extending inwardly from said arms, hangers having cam slots engaged by said studs, said cam slots having a slope intermediate the ends thereof, a seat hingedly connected at each side to a hanger said hanger being slidably movable relative to said

arms to cause said seat to move rectilinearly toward and away from the frame with an accompanying forward and backward movement.

4. A chair of the type described, comprising a frame providing arms and a back, hangers forming sides, sliding pivotal connections between said hangers and said arms, a seat of smaller external dimensions than the corresponding internal dimensions of the frame hingedly connected at each side to a hanger, a back member hingedly secured to said seat, and means for securing said back member to said back when the chair is expanded, said connections forming means whereby said seat, hangers and back member are movable to lie substantially within the confines of the frame.

5. A chair of the type described comprising a frame providing arms, hangers hingedly depending from said arms, a seat of smaller external dimensions than the corresponding internal dimensions of the frame, sliding pivotal connections between the seat and said hangers, said seat being movable into position substantially within the confines of the frame, and said hangers being movable to lie substantially parallel to the seat when the chair is collapsed, and an attaching member hingedly secured to said frame and movable into position to hold said frame, seat and hangers in their relative collapsed positions.

6. A chair of the type described comprising a frame providing arms, hangers pivotally connected to said arms and being provided with slots, a seat, studs extending through said slots and fastened to said seat to form sliding pivotal connections between the seat and the hangers, the connections between the hangers and the frame and the seat forming means whereby said seat is movable rectilinearly toward and away from said frame to collapsed and expanded positions respectively and said hangers are foldable against one side of the seat when the seat is in collapsed position.

7. A chair of the type described, comprising a frame providing arms and a back, hangers pivotally connected to said arms and being provided with slots, a seat, studs extending through said slots and fastened to said seat to form sliding pivotal connections between the seat and the hangers, said connections forming means whereby said seat is movable rectilinearly toward and away from said frame to collapsed and expanded positions respectively and said hangers are foldable against one side of the seat when the seat is in collapsed position, a back member hingedly secured to said seat, and means for securing said back member to said frame back when the chair is expanded.

8. A chair of the type described comprising a frame providing arms and a back, hangers forming sides, sliding pivotal connection between said hangers and said arms, a seat of smaller external dimensions than the corresponding internal dimensions of the frame hingedly secured at each side to a hanger, a back member hingedly secured to said seat, means for securing said back member to said frame back when the chair is expanded, said connections forming means whereby said seat, hangers and back member are movable to lie substantially within the confines of the frame, and spacers extending rearwardly from the bottom of said back member when the chair is in expanded position.

9. A chair of the type described comprising a frame providing arms, hangers hingedly depending from said arms, a seat of smaller external

- dimensions than the corresponding internal dimensions of the frame, sliding pivotal connections between the seat and said hangers, the connections between the hangers and the arms and the 5 seat forming means whereby said seat is movable into position substantially within the confines of the frame and said hangers are movable to lie substantially parallel to the seat when the chair is collapsed.
10. A chair of the type described comprising a frame member, a seat member and hangers, hinge connections between the hangers and one of said members and sliding pivotal connections between the hangers and the other member, said connections forming means operable for relative substantially rectilinear movement between the members when the chair is expanded and collapsed and for folding the hangers inwardly to lie adjacent to a surface of the seat member when 15 the chair is collapsed.
11. A chair of the type described comprising a frame member, a seat member and hangers, hinge connections between the hangers and one of said members, and sliding pivotal connections between the hangers and the other member, said connections forming means operable for relative substantially rectilinear movement between the members when the chair is expanded and collapsed and for folding the hangers inwardly to lie adjacent to a surface of the seat member when the chair is collapsed, and means for limiting relative movement between the members. 20
12. A chair of the type described comprising a frame member, a seat member and hangers, hinge connections between the hangers and one of said members, and sliding pivotal connections between the hangers and the other member, said connections forming means whereby said chair is expanded and collapsed by relative substantially rectilinear movement between the members and said hangers are foldable inwardly to lie adjacent to a surface of the seat when the chair is collapsed. 25
13. A chair of the type described comprising a frame member, a seat member and hangers, hinge 30 connections between the hangers and one of said members, and sliding pivotal connections between the hangers and the other member, said connections forming means whereby said chair is expanded and collapsed by relative substantially rectilinear movement between the members and said hangers are foldable inwardly to lie adjacent to a surface of the seat when the chair is collapsed. 35
14. A chair of the type described comprising a frame member providing arms, a seat member, and plate-like hangers forming sides, hinge connections between the hangers and one of said members, and sliding pivotal connections between the hangers and the other member, said connections forming means whereby said chair is expanded and collapsed by relative substantially rectilinear movement between the members and said hangers are foldable inwardly to lie adjacent to a surface of the seat when the chair is collapsed. 40
15. A chair of the type described comprising a frame member providing arms, a seat member of smaller external dimensions than the corresponding internal dimensions of the frame, and plate-like hangers forming sides, hinge connections between the hangers and one of said members and sliding pivotal connections between the hangers and the other member, said connections forming means operable for relative substantially rectilinear movement between the members to cause said seat member and hangers to lie substantially within the confines of the frame member when the chair is collapsed and with the hangers folded to lie adjacent to a surface of the seat member. 45
16. A chair of the type described comprising a frame member, a seat member, and hangers, hinge connections between the hangers and the frame, and sliding pivotal connections between the hangers and the seat, said connections forming means whereby said chair is expanded and collapsed by relative substantially rectilinear movement between the members and said hangers are foldable inwardly to lie adjacent to a surface of a seat when the chair is collapsed. 50
